NECK BEARING OILER FOR CREAM
SEPARATORSWilliam H. Harstick, Milwaukee, Wis., assignor
to International Harvester Company, a corpo-
ration of New Jersey

Application April 4, 1935, Serial No. 14,625

2 Claims. (Cl. 184—13)

The invention relates generally to centrifugal cream separators of the type embodying a separator bowl carried by the upper end of a vertically disposed drive spindle, said spindle having its lower end associated with a thrust bearing and its upper end adjacent the bowl associated with a so-called flexible neck bearing. This structure, with the exception of the bowl, is located in an oil containing housing wherein a large drive or ring gear picks up oil to splash it to the parts requiring lubrication. The neck bearing mentioned, however, is so located in the top of the housing as to make splash lubrication thereof too uncertain, and, accordingly, this invention more particularly relates to improved means for insuring positive and effective lubrication of said neck bearing.

The primary object of the invention, accordingly, is to provide an improved means for oiling cream separator neck bearings.

Another object is to provide a simple means for oiling cream separator spindle neck bearings, which means may be easily associated with certain standard types of cream separators without materially changing the structure thereof.

Still another object of the invention is generally to improve the operating efficiency of cream separators.

Other important objects will become apparent to those skilled in this art as the disclosure is more fully made.

Briefly, such important objects may be attained in a conventional type of cream separator, having an oil containing housing, in which is located a ring gear that drives the vertical spindle upon which is carried the separator bowl outside said housing. The top of the housing is depressed to form a well in which to locate the bowl. In the bottom of this well is fitted a flexible neck bearing for journaling the upper end of the drive spindle. The ring gear rotates rapidly to pick up oil and splash it around the interior of the housing to lubricate such parts as require lubrication, but, as the neck bearing is located in a manner making it difficult for the gear to throw oil thereto, this invention provides a special oil trap, or catcher, located effectively to receive oil thrown tangentially off the rim of said drive gear. This trapped oil is then lead by gravity feed through a passage in the well bottom that communicates with a spout that serves to drip the oil directly and continuously on the neck bearing for the purpose of positively lubricating the same.

In the accompanying sheet of drawings illus-

trating a practicable form of the invention as applied to a conventional cream separator,—

Figure 1 is a vertical sectional view through the cream separator structure, showing the improved neck bearing oiler;

Figure 2 is a detail elevational view of the oil trap; and,

Figure 3 is a plan sectional view of the neck bearing cover plate taken along the line 3—3 of Figure 1, looking in the direction of the arrows. 10

The cream separator comprises a stand 10, on which is carried a gear housing 11 having a bath of oil 12 therein. The upper portion of said housing is depressed to form a well 13 having a bottom 14 formed with an opening to receive 15 an annulus 15 supporting a neck bearing 16 held, yieldingly or flexibly, by the annular spring 17. This bearing assembly is closed at its top by a cover plate 18.

The cover plate 18 has an opening centrally formed therein for enabling a vertically disposed drive spindle 19 to be passed therethrough, said spindle shaft being journaled at its upper end in the flexibly mounted bearing structure described. Mounted on the upper end of the spindle 19, within the recess or well 13, in the usual way, is the centrifugal cream separator bowl 20. The spindle at its lower end is mounted on a ball bearing 21 and is also journaled in another thrust bearing 22 appropriately mounted in the wall of the housing 11, as shown. The spindle includes a gear 23 driven from a large ring gear 24 journaled on a transverse shaft 25 mounted suitably in the housing 11. 20

As the gear 24 rotates, it picks up oil to throw it upwardly and splash it within the housing on the parts therein requiring lubrication. Because of the location of the neck bearing 16 in the bottom 14, it is difficult for the same to receive effectively a satisfactory supply of the lubricant. Obviously, the tangential throw of oil from the gear 24 is such that it is not directed in sufficient quantity to this neck bearing and, as it is highly important properly to lubricate said bearing, the following structure is provided to solve this problem. 30

On a face portion of the well 13, directly in line with the maximum tangential throw of oil coming from the gear 24, as indicated by the arrow lines, is secured by screws 25' a plate 26 (see Figure 2) having a pressed out oil trap portion 27 closed at its bottom to hold oil and open at its top to receive or trap the oil splashed thereto. The lower end of this oil trap 27 communicates with a transverse downwardly inclined 40

bore, or passage, 28 formed in the bottom 14, as shown, said bore serving to lead the oil toward the bearing 16 which is to be lubricated. This bore 28 is in communication with a short up-standing pipe 29 located in a bore provided in the bottom 14 and overhanging flange of the annulus 15, as shown in Figure 1. The oil is thus led to a point under the cover plate 18 where it is received by a conduit 30 radially formed in the plate 18, as shown in Figure 3. The end of this conduit 30 terminates at a point directly over the balls in the bearing 16, where the lower portion of the terminal end of said conduit is formed with a bent down spout 31, from which the oil will drip in an obvious manner onto the bearing.

It is observed that the column of liquid or oil in the trap 27 will always be higher than the column of oil in the vertical pipe 29 and, as a result, the oil will continuously flow from the trap through the bore 28 and conduit 30, from whence it drips off the spout lip 31 onto the bearing where it is needed.

The operation of this improved neck bearing 25 oiler is simple, fool-proof, and effective, the same insuring positive and ample delivery of oil to the bearing all the while the cream separator is working and the ring gear 24 is turning.

It must now be appreciated that an improved 30 oiler for the purpose described has been provided, which attains all of the desirable objects of the invention heretofore recited.

The intention is to cover all changes and modifications of the preferred example chosen for 35 purposes of the disclosure which do not in material respects depart from the spirit and scope of the invention, which is covered by the appended claims.

What is claimed is:

- 40 1. In a cream separator having an oil containing gear housing formed at its upper end with a vertical wall forming a bowl recess having a horizontal floor with an opening therethrough, a collar carried on the floor and suspended in said opening, said collar including a radially inwardly disposed annular vertical wall, a ball bearing unit carried on the said annular wall, said bearing journaling the upper end of an upright spindle the lower end of which is

5 journaled in the bottom of the gear housing, an annular flexible member carried in the collar and having a portion in which the ball bearing unit is yieldably disposed, a gear in the housing which splashes oil from the bottom of the housing to a wall of the bowl receiving recess, the combination therewith of an oiling means for the ball bearing unit comprising a cover plate having an aperture through which the spindle is passed, means for securing the plate to the collar, 10 said plate being formed with a radial oil duct to drip oil onto the balls in the ball bearing unit, a trap mounted on the outside of the bowl recess wall for catching splashed oil from the gear, and a conduit leading from the trap through the bowl 15 recess floor and the collar to said duct.

2. In a cream separator having an oil containing gear housing formed at its upper end with a vertical wall providing a bowl recess having a horizontal floor with an opening therethrough, a collar carried on the floor and suspended in said opening, said collar including a radially inwardly disposed annular vertical wall, a ball bearing unit carried on the said annular wall, said bearing journaling the upper end of 25 an upright spindle the lower end of which is journaled in the bottom of the gear housing, an annular flexible member carried in the collar and having a portion in which the ball bearing unit is yieldably disposed, a gear in the housing which splashes oil from the bottom of the housing to the outer surface of the wall of the bowl receiving recess, the combination therewith of an oiling means for the ball bearing unit comprising a cover plate having an aperture 30 through which the spindle is passed, means for securing the plate to the collar, said plate including a radial oil duct to drip oil onto the balls in the ball bearing unit, a trap on the outer surface of the wall of the bowl recess for catching 40 splashed oil from the gear, and a passage formed in the horizontal floor including a continuation thereof extending through the collar for leading oil from the trap to said duct, the terminal inner end of the duct formed with a lip disposed 45 directly over the balls in the bearing unit to drip the oil thereonto.

WILLIAM H. HARSTICK.
